UNITED STATES PATENT OFFICE

162,404

POOL TABLE COVER

John B. Gregory, Frederick, Okla.

Application August 22, 1949, Serial No. 4,643

Term of patent 7 years

(Cl. D92—26)

To all whom it may concern:

Be it known that I, John B. Gregory, a citizen of the United States, residing at Frederick, in the county of Tillman and State of Oklahoma, have invented a new, original, and ornamental Design for a Pool Table Cover, of which the following is a specification, reference being had to the accompanying drawing, forming part thereof.

I claim:

The ornamental design for a pool table cover, as shown.

JOHN B. GREGORY.
